UNITED STATES PATENT OFFICE.

FRANK R. BOLZ, OF SOMERVILLE, MASSACHUSETTS.

CONVERTIBLE TRUNK.

Application filed February 28, 1925. Serial No. 12,264.

This invention relates to a trunk which includes a body member, a hinged lid member, and a tray member adapted to partially enter and be supported by the body member and covered by the lid member when the trunk is closed, as in the ordinary so-called steamer trunk.

The object of the invention is to provide in a trunk characterized as above stated, improved means whereby the tray member may be engaged with the body member to swing thereon to position to serve as a wardrobe and firmly supported in its wardrobe position, by hangers connecting the tray member with the body member, and by coupling parts connecting the lid member with the tray member.

Of the accompanying drawings forming a part of this specification:—

Figure 1 is a perspective view, showing a trunk embodying the invention, the tray member being in its wardrobe position.

Figure 2 is a section on line 2—2 of Figure 1.

Figure 3 is a fragmentary perspective view, showing portions of the lid member and the tray member, and coupling parts separably connecting said members.

Figure 4 is a fragmentary perspective view, showing portions of the body member and the tray member disengaged from each other, and members of one of the hinges connecting the tray member with the body member.

Figure 5 is a section on line 5—5 of Figure 2.

The same reference characters indicate the same parts in all of the figures.

12 designates the body member, 13 the lid member, and 14 the tray member, the lid member being connected with the body member by the usual hinges (not shown). Said members may be adapted to constitute a steamer trunk, the bottom of the tray member being within the body member and bearing on internal supporting means 15 in the latter, as usual.

An end wall of the tray member is engaged with an end wall of the body member, by hinges permitting movement of the tray member from a horizontal position, with its bottom within the body member, to a vertical position, as shown by Figure 1, and by full lines by Figure 2, the tray member being thus converted into an element of a wardrobe trunk.

The hinges are separable, to permit the disengagement of the tray member from the body member, each hinge being preferably composed of a socketed leaf 16, fixed to an end wall of the body member, a socketed leaf 17, fixed to an end wall of the tray member, and a pintle 18, removably inserted in, and connecting the sockets of said leaves, and provided with a head 19, whereby it may be inserted and removed.

The hinge leaves 16 are attached to an end wall of the body member and are located within the latter, and the hinge leaves 17 are attached to an end wall of the tray member and are located between the bottom and the outer edge or mouth of the tray member, as shown by Figures 2 and 4. In consequence of this hinge arrangement, when the tray member is elevated to a vertical position, its hinge-engaging end wall is supported by the hinge-engaging end wall of the body member, and its bottom overhangs a portion of the interior of the body member, and is located in the path of movement of the lid member, so that the lid member cannot be closed when the tray member is elevated, and the lid member when opened, may be adapted by the coupling parts next described, to cooperate with the hinges in maintaining the tray member in an elevated or upright position. Said coupling parts preferably include one of the usual bolts 20, provided on the swinging edge of the lid member 13, to engage a keeper 21, on the outer wall of the body member. I modify the bolt 20, by providing it with an orifice 22 (Figure 3), adapted to receive a hook 23, jointed at 24 to the bottom of the tray member, said hook constituting the other coupling part. The arrangement is such that the coupling parts may be interengaged when the tray member is in a vertical position, and the lid member is opened. If desired, the tray member may be additionally maintained in an upright position by a swinging brace 25, pivoted at 26 to the front wall of the body member, and a headed stud 27, fixed to the front wall of the tray member, and adapted to engage a notch in the swinging end of the brace 25, as shown by Figure 1.

When the tray member is provided with the usual garment hangers 28, and compressor 29, it is adapted to serve as a wardrobe.

It not infrequently happens that the hangers, or some of them, are broken by

rough usage, when the tray is within the trunk body and garments are engaged with the hangers. In case of such breakage the hangers and the compressor, which are 5 temporarily detachable from the tray member, may be removed, and the hinge pintles 18 may be removed from the hinge sockets. The tray member is thus converted into an ordinary tray, in which the garments formerly 10 engaged with the hangers, may be packed, the tray member being adapted to be inserted in and removed from the body member, as in an ordinary non-convertible trunk.

15 I prefer to include in the coupling shown by Figure 3, a tongue 30, having a slot 31, formed to receive the bolt 20. The tongue is secured by rivets 32 to the inner side wall of the tray member, and when engaged 20 with the bolt, prevents any looseness of the tray member which would otherwise be permitted by the hook 23. The hook prevents withdrawal of the bolt 20 from the tongue slot.

25 I claim:—

1. A convertible trunk comprising a body member, a hinged lid member having a coupling part on its swinging edge, a tray member having a complementary coupling 30 part on its bottom, hinges connecting one end of the body member with the corresponding end of the tray member, the hinges being arranged to permit the location of the tray member in a horizontal position 35 with its bottom and coupling part within the body member, and in a vertical position with its bottom overhanging a portion of the interior of the body member, and its

coupling part in position to engage the coupling part on the swinging edge of the lid member, when the latter is opened, the arrangement being such that the interengagement of said coupling parts causes the lid member to cooperate with the hinges in maintaining the tray member in a vertical 45 position.

2. A convertible trunk as specified by claim 1, one of said coupling parts being a bolt fixed to the swinging edge of the lid member, and provided with an orifice, another coupling part being a hook jointed to the bottom of the tray member, and adapted to enter said orifice when the tray member is vertical and the lid member is opened.

3. A convertible trunk comprising a body member; a hinged lid member; a tray member; hinges engaging one end of the body member with the corresponding end of the tray member, the arrangement being such that the hinges permit movement of the tray member from a horizontal position with its bottom in the body member, to a vertical position, converting the tray member into an element of a wardrobe trunk; a bolt fixed to the lid member and provided with an orifice, a tongue fixed to the tray member and provided with a slot, adapted to receive the bolt member, and a hook jointed to the tray member and adapted to enter the bolt orifice, said bolt, tongue, and hook constituting a coupling adapted to secure the tray member in an upright position when the lid member is opened.

In testimony whereof I have affixed my signature.

FRANK R. BOLZ.
